US0D1112191S

(12) **United States Design Patent** (10) **Patent No.:** **US D1,112,191 S**
(45) **Date of Patent:** **** Feb. 10, 2026**

(54) **MAGNETIC VEHICLE-MOUNTED SUPPORT FOR PHONE OR NAVIGATION DEVICE**

(71) Applicant: **Weiyu (Shenzhen) Technology Co., Ltd.**, Guangdong (CN)

(72) Inventor: **Guichuan Zhou**, Guangdong (CN)

(73) Assignee: **Weiyu (Shenzhen) Technology Co., Ltd.**, Shenzhen (CN)

(**) Term: **15 Years**

(21) Appl. No.: **29/907,914**

(22) Filed: **Jan. 10, 2024**

Related U.S. Application Data

(63) Continuation-in-part of application No. 35/515,678, filed on Oct. 19, 2022 (U.S. filing date under 35 U.S.C. 384), and having an international filing date of Oct. 19, 2022, now abandoned.

CLAIM

The ornamental design for a magnetic vehicle-mounted support for phone or navigation device as shown and described.

DESCRIPTION

FIG. 1 is a front and right side perspective view of a magnetic vehicle-mounted support for phone or navigation device showing my new design;

FIG. 2 is a rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a cross-sectional view taken along line 9-9 of FIG. 4.

The broken lines in the drawings illustrate portions of the magnetic vehicle-mounted support for phone or navigation device which form no part of the claimed design.

1 Claim, 9 Drawing Sheets
